UNITED STATES PATENT OFFICE.

EDGAR D. MISNER, OF DETROIT, MICHIGAN, ASSIGNOR OF ONE-FIFTH TO JULIUS J. BATTENFELD AND ONE-FIFTH TO HENRY RETZ, BOTH OF DETROIT, MICHIGAN.

WRINGER.

REISSUED

Application filed May 20, 1921. Serial No. 471,136.

To all whom it may concern:

Be it known that I, EDGAR D. MISNER, a citizen of the United States of America, residing at Detroit, in the county of Wayne 5 and State of Michigan, have invented certain new and useful Improvements in Wringers, of which the following is a specification, reference being had therein to the accompanying drawings.

- 10 The invention relates to wringers and refers particularly to the power driven type. The invention has for one of its objects the provision of means which is rotatable in opposite directions to predetermined positions 15 to move one of the rolls of the wringer toward the other and to hold this movable roll under different tension; and also the provision of a cam member having inclined faces terminating in off-set steps for cooperating with the rotatable tensioning member to move the movable roll of the wringer toward the other upon rotation of the tensioning member and to hold the same in either of its adjusted positions. The invention 20 has for another object, the provision of equalizing means for facilitating the simultaneous and equal movements of the opposite ends of the movable roll when moving away from the other roll. Further objects of the invention reside in the novel features of construction as more fully hereinafter set forth.

In the drawings:

Figure 1 is a side elevation partly broken away and in section, of a wringer embodying my invention;

Figure 2 is a top plan view thereof;

Figure 3 is a cross section on the line 3—3 of Figure 1;

Figure 4 is a bottom plan view of the stepped cam member;

Figure 5 is a cross section on the line 5—5 of Figure 2.

1 is the frame of the wringer formed of the complementary sections 2 and 3 which are suitably secured to each other as by means of the machine screws 4. 5 is the power driven roll and 6 the cooperating roll. The shaft 7 of the power driven roll is rotatably mounted in bearing blocks 8 at its opposite ends which are positioned between the complementary sections 2 and 3. 9 is a gear secured to one end of the shaft 7 and adapt-

ed to mesh with the gear 10 secured to the corresponding end of the shaft 11 of the cooperating roll, these two gears being enclosed within the enlargement 12 formed upon the complementary sections 2 and 3. 13 are bearing blocks located at the opposite ends of the shaft 11 and slidably engaging between the complementary sections 2 and 3 of the frame.

The bearing blocks 8 and 13 are preferably formed of wood and impregnated with lubricant, each having the half bearing 14 for engagement with the shafts.

15 is a resilient bowed member extending above the cooperating roll 6 and having its ends engaging in rectangular apertures 16 in the upper end of the metal strips 17 which are at the inner sides of the bearing blocks 13 and have circular openings 18 near their lower ends for engagement with the shaft 11, these circular apertures being of sufficient diameter so that when the cooperating roll 6 is moved toward the power driven roll 5 by means of the ends of the resilient bowed member contacting with the tops of the bearing blocks 13, the shaft 11 will contact with the half bearings in the bearing blocks 13. 19 is a tensioning rod extending transversely of the resilient bowed member 15 and longitudinally movable in the cam member 20 secured centrally to the top of the frame 1. This tensioning rod is secured at its lower end to the clip 21 by means of the screw 22 threadedly engaging the clip and extending into the annular groove 23 in the tensioning rod. The lower portion of the clip is U-shaped to embrace the center of the resilient bowed member 15.

For the purpose of facilitating the movement of the cooperating roll 6 toward the power driven roll 5, the cam member 20 has the pairs of cam or inclined faces 24 and 25 at the lower ends of which are the shoulders 26 or steps 26 and 27 respectively, and the tensioning rod 19 has the transverse projection 28, which is preferably a pin, extending out from one side thereof for engagement with these inclined faces and steps, the particular face and step being dependent upon the direction of the rotation of the tensioning rod. The transverse pin 28 is normally between the upper ends of the inclined faces when

there is no tension upon the resilient bowed member 15 so that this pin is in position to engage the inclined faces and to ride down over the same upon rotation of the tensioning rod to place the resilient bowed member under tension and to move the cooperating roll 6 toward the power driven roll 5 by means of the bearing blocks 13. The steps 26 and 27 are at different heights so that a 10 different predetermined tension is placed upon the resilient bowed member when the transverse pin is in engagement with each of these steps.

To release the pressure of the cooperating roll upon the power driven roll it is merely necessary to rotate the tensioning rod 19 to disengage its transverse pin 28 from its engaged step, when the pin will ride up over an inclined face. The handle 29 is provided at the upper end of the tensioning rod for rotating the same to move the cooperating roll 6 toward the power driven roll or for disengaging the transverse pin from its engaged step and to prevent rotation of this handle upon releasing the pressure, and after the transverse pin 28 has moved over an inclined face, the upper portion of the cam member 20 has the diametrically opposite slots 30, the walls of which connect into 30 the upper ends of the inclined faces.

To facilitate the simultaneous and equal movements of the opposite ends of the cooperating roll 6 when moving away from the power driven roll 5, the lower end of the tensioning rod 19 has the recess 31 to receive the coil spring 32. When the tensioning rod is in either of its innermost positions to tension the resilient bowed member 15, the latter rests against the lower end of the tensioning rod; but when the mechanism is tripped, the spring 32 will clamp the resilient bowed member against the base 33 of the U-shaped portion of the clip 21, which base forms an extended bearing for the resilient bowed member and thereby prevents rocking movement of the resilient bowed member relative to the tensioning rod. This resilient bowed member is preferably formed with the lug 34 which is engageable within 45 the lower convolution of the coil spring 32 to longitudinally position the resilient bowed member. The bearing blocks 13 also preferably have their sides slightly tapering to avoid too great a frictional resistance to 50 their movements.

To limit the upward movement of the cooperating roll 6 when the mechanism is tripped, the complementary sections 2 and 3 of the wringer frame are spaced apart a 60 distance less than the diameter of the cooperating roll and have the transversely extending flanges 35 which are adapted to be engaged by the cooperating roll. To drain any water which drops off the ends of the 65 rolls inwardly away from the ends of the

wringer frame, there are inwardly extending and downwardly inclined flanges 36 beneath the power driven roll.

What I claim as my invention is:

1. In a wringer, the combination with a 70 frame and a pair of rolls mounted thereon, of a rotatable tensioning rod connected to one of said rolls for moving the same toward the other, and a cam member cooperating with said tensioning rod to compel longitudinal movement thereof upon rotation thereof, said cam member having steps offset from each other longitudinally of said rod for positioning said tensioning rod.

2. In a wringer, the combination with a 80 frame, of a pair of rolls, a resilient bowed member connected to one of said rolls to move the same toward the other, a cam member having a pair of offset steps, a tensioning member connected to said resilient 85 member to tension the same to move said movable roll toward the other, and a transverse projection upon said tensioning member engageable with either of said steps to maintain said resilient member under tension, said tensioning member being rotatable in opposite directions to engage said projection with either of said steps and to disengage said projection from said step.

3. In a wringer, the combination with a 95 frame and a stepped cam member, of a pair of rolls, a resilient member connected to one of said rolls to move the same toward the other, a vertical tensioning rod longitudinally slidably engaging said cam member and connected to said resilient member, and a transversely extending pin upon said tensioning rod engageable with the steps of said cam member, said shaft being rotatable in opposite directions to engage said transversely extending pin with either of the steps of said cam member, the steps being offset longitudinally of said rod from each other.

4. In a wringer, the combination with a 110 frame and a cam member thereon having a slot in its upper portion, inclined faces in its lower portion merging into the walls of said slot and shoulders at the lower ends of said inclined faces, of a pair of rolls, a resilient member connected to one of said rolls to move the same toward the other, a tensioning member slidably engaging said cam member and connected to said resilient member, and a transversely extending pin 115 upon said tensioning member adapted to pass through said slot and engage either of said inclined faces and its shoulder upon rotation of said tensioning member.

5. In a wringer, the combination with 125 a frame, and a cam member thereon having diametrically opposite slots in its upper portion and pairs of inclined faces in its lower portion, each pair terminating at its lower end in steps and said steps 130

- being longitudinally offset from each other, of a pair of rolls, a resilient member connected to one of said rolls for moving the same toward the other, a tensioning member slidably engaging said cam member and connected to said resilient member, and 5 a transversely extending pin upon said tensioning member adapted to pass through either of said slots and to engage upon rotation in either direction an inclined face and the step at its lower end.
6. In a wringer, the combination with a frame, of a pair of shafts, rolls carried by said shafts, upper and lower bearing blocks 15 for said shafts mounted in said frame, a resilient member having the opposite ends thereof slidably engaging said upper bearing blocks for moving one of said rolls toward the other, means for actuating said resilient member, and members at the sides of said upper bearing blocks having means at their upper ends for receiving the opposite ends of said resilient member and provided with means near their lower ends for engagement 20 with the shaft of said movable roll.
7. In a wringer, the combination with a frame and a pair of rolls mounted thereon, of movable means rotatable in opposite directions for moving one of said rolls toward the other, and means for holding said rotatable means in different predetermined positions when said movable roll is moved 25 toward the other.
8. In a wringer, the combination with a frame, of a pair of rolls, a resilient bowed member connected to one of said rolls to move the same toward the other, a tensioning rod connected to said bowed member for tensioning the same to move said movable 30 roll toward the other, a transverse pin upon said tensioning rod, a cam member having an inclined face cooperating with said pin to longitudinally move said tensioning rod, and a step cooperating with said pin to hold said tensioning rod in adjusted position, said rod being rotatable to move said pin over said inclined face to tension said bowed member and to disengage said pin from said step.
9. In a wringer, the combination with a frame and a pair of rolls mounted thereon, of a rotatable tensioning rod for moving one of said rolls toward the other, a transverse pin upon said tensioning rod, means cooperating with said pin for holding said tensioning rod in adjusted position, and a pair of spaced cams carried by said frame and cooperating with said pin to move said rod longitudinally.
10. In a wringer, the combination with a frame and a pair of rolls mounted thereon, of a rotatable tensioning rod for moving one of said rolls toward the other, a transverse pin upon said tensioning rod, means cooperating with said pin for holding said tensioning rod in adjusted position, and a cam 45 member having open slots therethrough and provided with cammed surfaces in said slots for engaging said transverse pin upon rotation of said tensioning rod in either direction for moving said tensioning rod longitudinally.
11. In a wringer, the combination with a frame, of a pair of rolls, a resilient member connected to one of said rolls for moving the same toward or away from the other of said rolls, a longitudinally movable member slidably engaging the top of said frame, a clip between said longitudinally movable member and said resilient member, and yieldable means for clamping said resilient member against said clip.
12. In a wringer, the combination with a pair of rolls, of a member connected to one of said rolls and adapted to move the same toward the other, a tensioning rod loosely connected to said member and adjustable to move the same and the roll connected thereto toward the other roll, said rod being adapted to be held in an adjusted position, and yieldable means for holding said member in a predetermined position with respect to said rod when said rod is released.
13. In a wringer, the combination with a pair of rolls, of a member, means between the ends of one of said rolls and said member for moving said roll by said member, a tensioning rod connected to said member and adjustable to move the roll actuated thereby toward the other roll, said rod being adapted to be held in an adjusted position and permitting of rocking movement of said member relative thereto, and yieldable means between said rod and member for holding said member in a predetermined position relative to said rod when said rod is released.
14. In a wringer, the combination with a frame and a pair of rolls mounted thereon, of a rotatable and longitudinally movable member for moving one of said rolls toward the other, and means cooperating with said member upon rotation thereof for longitudinally moving said member and holding the same in a predetermined position, said member being rotatable in either direction to release the same.
15. In a wringer, the combination with a frame and a pair of rolls mounted thereon, of a rotatable and longitudinally movable member for moving one of said rolls toward the other, and a member cooperating with said first-mentioned member upon rotation thereof for longitudinally moving said first-mentioned member and holding the same in a predetermined position, one of said members having a step and inclined faces leading to said step, and the other of said members having a projection engageable with said step and faces, said first-mentioned member being rotatable in either direction to disengage said step and projection.

16. In a wringer, the combination with a frame and a pair of rolls mounted thereon, of a tensioning rod adjustable longitudinally in one direction for moving one of said rolls toward the other, a projection on said tensioning rod, and means for holding said tensioning rod in an adjusted position comprising a member provided with a step and inclined faces converging toward said step, said step and faces being engageable with 10 said projection, and said tensioning rod being rotatable in either direction to disengage said projection, from said step.

In testimony whereof I affix my signature.

EDGAR D. MISNER.
